United States Patent Office

Des. 224,861
Patented Oct. 3, 1972

224,861

CHAIR

Morris F. Fisher, Carmel, Ind., assignor to Mohasco
Industries, Inc., Amsterdam, N.Y.

Filed Jan. 6, 1971, Ser. No. 104,540

Term of patent 14 years

Int. Cl. D6—02

U.S. Cl. D6—71

The figure is a perspective view of a chair embodying my new design. The side not shown is like the side shown except for the omission of the magazine holder, while the back of the chair is conventionally plain and unornamented.

I claim:

The ornamental design for a chair, substantially as shown and described.
